(57) **CLAIM**

The ornamental design for a hair dryer with a night light, as
shown and described.

DESCRIPTION

FIG. 1 is a perspective view of the preferred embodiment of
a hair dryer with a night light showing my new ornamental
design;

FIG. 2 is a side view of the preferred embodiment of FIG.
1;

FIG. 3 is a top plan view of the preferred embodiment of
FIG. 1;

FIG. 4 is a bottom plan view of the bottom of the preferred
embodiment of FIG. 1;

FIG. 5 is a front elevational view of the preferred embodiment
of FIG. 1; and,

FIG. 6 is a rear elevational view of the preferred embodiment
of FIG. 1.

The broken lines in FIGS. 1, 2, 4, 5, and 6 are for illustrative
purposes only and forms no part of the claimed design.
